UNITED STATES PATENT OFFICE.

GORDON A. JOHNSTONE, OF ATLANTA, GEORGIA.

WARP-CONTROLLING DEVICE FOR LOOMS.

1,294,804.

Specification of Letters Patent. Patented Feb. 18, 1919.

Application filed May 9, 1917. Serial No. 167,573.

To all whom it may concern:

Be it known that I, GORDON A. JOHNSTONE, a citizen of the United States, residing at Atlanta, in the county of Fulton, 6 State of Georgia, have invented certain new and useful Improvements in Warp-Controlling Devices for Looms, of which the following is a specification.

My invention relates to looms and consists of an improved device for controlling the tension of the warp-yarns during the weaving operation. The object of my improvement is to regulate the tension on the two sets of warp-yarns manipulated by the harnesses to provide for a uniform spacing or distribution of the yarns at the fell of the fabric whereby to prevent the appearance of "reediness" or unevenness in the cloth.

20 In weaving most varieties of goods it is the general practice to draw the warp through the harness one end to a heddle, alternating between front and back harnesses, while in the reed two yarns are drawn through each dent. This tends to segregate the yarns in pairs at the fell of the cloth, preventing them from being uniformly distributed and equally spaced thereacross, and hence causing what is known as "reediness" in the finished fabric. Stated briefly, the tension on the warp draws the yarns together where they pass through the reed dents in pairs, and this causes uneven spacing or pairing of the yarns in the fabric. To overcome this defect in fine goods it has sometimes been the practice to employ twice the usual number of dents to the reed, with each yarn drawn through a separate dent. Such a method cannot be 40 used in most classes of weaving, however, since it seriously interferes with production and consequently increases the cost of the goods.

Various expedients in the adjustment of 45 the loom have heretofore been attempted to eliminate this defect of reediness or uneven spacing of the warp-yarns, but in most cases the tension on the warp has been increased to such an extent as to cause bad 50 weaving and slow production. With my present improvement I control the yarns at the same distance back of the harness as the fell of the cloth is from the front thereof, thereby equalizing the tension on the 55 separate yarns while raising the warp higher at this point than at the whip-roll. This

arrangement allows the upper warp-yarns to remain relatively slack while the filling is being put in whereby when the filling is being beaten up the whole series of yarn 60 will be equalized in their distribution across the loom to prevent unequal spacing and consequent reediness in the cloth.

The manner and means for carrying out the improvement are fully described in the 65 following specification, illustrated by the accompanying drawings, in which like reference characters designate like parts. In the drawings:—

Figure 1 is a perspective view of a portion 70 of a loom showing my improved attachment applied to use thereon;

Fig. 2, a diagrammatic view illustrating the unequal spacing of the warp-yarns in the fabric which causes the "reedy" appear- 75

Fig. 3, a similar view showing the uniform spacing or distribution of the warp-yarns as effected by the use of my new apparatus whereby the cloth is improved 80 in its texture and finish;

Fig. 4, an enlarged, perspective view of my improved device showing the means for adjustably attaching it to the loom-frame;

Fig. 5, a detail view of a portion of the 85 attachment;

Fig. 6, a view showing a modification in the arrangement and method of operation of the mechanism; and

Figs. 7, 8 and 9, diagrammatic views 90 showing the manner in which the device functions during the several steps in the weaving operation of the loom.

Referring to the drawings, in Fig. 1, A designates one side of a loom-frame of usual 95 construction, B the beam on which the warp W is wound, and R the whip-roll over which the yarns w draw to the harnesses H, H'. My improved warp-controlling device extends across the loom at a point ap- 100 proximately midway between the rear harness and the whip-roll and preferably at the same distance back of the harness as the fell is in front thereof. The apparatus comprises, essentially, two parallel, trans- 105 verse bars or lease-rods L, L' adapted to be inserted through the separated sections w, w' of the warp W and supported at their ends to allow them to oscillate about a central axis. Extending across the loom be- 110 tween the lease-rods L, L' and parallel therewith is a fixed rest or support T for

the warp which may be constructed in the form of a round or flat rod or as a T-bar.

As illustrated more particularly in Fig. 4, the supports for the two lease-rods L, L'

5 and their intermediate warp-rest or fixed bar T comprises two frames F, F adjustably mounted on the top of standards S, S which are attached to the side-frames A of the loom by means of the clamp-brackets C, C.

10 Each bracket C consists of a substantially L-shaped plate channelled vertically to provide the projecting bearing-ribs c, c and formed with holes o, o' for receiving the bolts o, o, see Fig. 1, by which it is clamped

15 to the side of the frame A. The upright arm of the L-bracket C is adapted to fit within the slotted, lower end of the arm or standard S which is fastened thereto by means of the bolt b extending through the

20 vertical slot s, with a nut n and washer m at its end. Referring to Fig. 5, each frame F is constructed with two divergent arms f, f, formed with inclined slots v, v and connected by a central web f'. The web f' is

25 thickened at its center to form a bearing e, which is provided with a vertical slot t wherein the end of the fixed T-bar or warp-rest T is supported. To adapt the frames F to support a round rod K, which is some-

30 times used in place of the bar T, as shown in Fig. 5, the slot t is cored out at k to provide a cylindrical opening for the end of the rod. Projecting from the side of the bracket F is a base g adapted to set on the

35 top of the arm S. A bolt b' extends up through a slot s' in the arm S and through the base g, with a nut n' and washer m' on its end to clamp the parts together. The slots s in the bracket C provided for vertical

40 adjustment of the arm S, and the slots s' in the arm S allows for horizontal adjustment of the frame F so that the cross-bar T and its associated lease-rods may be set in different positions in relation to the other

45 parts of the loom.

The lease-rods L, L' are supported at their ends in the inclined slots v, v of the frames F, F to adapt them to play up and down in relation to the fixed bar T, or rod

50 K, as the case may be. As shown in Figs. 4 and 5 the sides of the slots v, v are prefer-

ably lined with strips of leather l, l or some other resilient material to prevent chafing and wear between the parts. It is also to be noted that the slots v, v are somewhat arc-

55 uate in contour, substantially concentric to a point midway between their upper ends. Through this arrangement the lease-rods L, L' are guided in their movement in more

60 or less arcuate paths about a central axis located above the top of the fixed bar T.

My improved device is attached to the loom by clamping the brackets C to the opposite side-frames A, as shown in Fig. 1, 65 with the bolts o, o passing through suit-

able slots as usually provided therein. The arms S are then fitted to the upper ends of the brackets C and secured thereto by means of the bolts b. The frames F are next placed

70 on top of the arms or standards S and fastened thereto by means of the bolts b', the slots s and s' allowing for vertical and horizontal adjustment of the frames F to bring them into opposite relation at the

75 correct height and at the proper distance in back of the harness H'. With the frames F, F in position as above described the fixed bar or warp-rest T is next set in place by inserting its ends in the vertical slot t, t.

Where a T-bar is employed for this purpose 80 its bottom flange or rib is cut away at the ends to allow its main bar to slide into the slots t, t. For most purposes a flat bar may

be used in place of the T-bar, but the latter form of rest provides a stiffer structure 85 and prevents sagging at the center when coarse yarns are being woven under relatively heavy tension. For very fine yarns

the light, round rod K, shown in Fig. 5, is substituted for the flat or T-bar T, with 90 its ends held in the openings k, k in the

frames F, F. 95

Referring now to Figs. 7, 8 and 9, the warp W is led up from the beam B over the whip-roll R and thence across the fixed support or rest T to the harnesses H, H'. One set of

yarns w is drawn through the heddles h' of the rear harness H' and the alternate yarns w' are threaded through the eyes of the heddles h in the front harness H. From 100 the harnesses H, H' the warp is drawn through the reed D, two ends w and w' to a dent, to the fell of the cloth where the filling is beaten up as represented at x. Both

sets of warp-yarns w and w' rest on the 105 top of the fixed bar or support T which is preferably raised slightly above the top of the whip-roll R, this setting being provided for on different types of looms through the

adjustment of the frames F, F as previously 110 explained. As shown in Fig. 7, it is the preferred practice to employ a front lease-

rod L of oval shape in cross-section while the rear rod L' is usually of cylindrical form. The two lease-rods L and L' are inserted 115

through the warp between the two sets of alternate yarns w and w', on either side of the fixed rest T, with their ends seated in

the inclined slots v, v of the frames F, F. One set of yarns w, indicated by the full 120 lines in Figs. 7 to 8, draws from the whip-

roll R across the top of the rear lease-rod L', thence over the fixed rest T and under the lease-rod L to the rear harness H'. The

other set of alternate yarns w', represented 125 by dot-and-dash lines, draws from the whip-

roll R in under the rear lease-rod L', thence across the fixed rest T and over the top of the front lease-rod L to the front harness H.

In other words the alternate yarns w and w' 130

cross at the top of the rest T with one set leading over the rear lease-rod L' and under the front rod L, while the other set leads under the rear lease-rod L' and over the front rod L.

Fig. 7 illustrates the front harness H raised and the rear harness H' lowered to their extremes of traverse, with the shed opened to receive the shuttle, which carries the weft or filling, and the lay Y at the back of its stroke. In Fig. 8 the two harnesses H and H' are shown in mean position, midway between the limits of their throw, with the lay Y carried forward to cause the reed D to beat up the filling at the fell x. As shown in Fig. 9, the lay Y has returned to the back end of its stroke, and the harnesses H and H' have been reversed to raise the set of yarns w and depress the other set w' to again open the shed to receive another length of weft thread. The movement of the harnesses H and H' vertically in alternately opposite directions separates the two sets of warp yarns to provide for the passage of the shuttle through the shed, one set of yarns being raised while the other is depressed, in the well known manner common to plain weaving. Meanwhile, this alternate shifting of the harnesses causes a corresponding up and down motion of the lease-rods L and L' under the influence of the two sets of yarns w and w'. This is provided for by the sliding of the lease-rods in the slots v, v of the frames F, F which allow for a rocking motion thereof as required. In Fig. 7 the yarns w are shown as supporting the front lease-rod L in raised position in relation to the fixed bar T, while the rear lease-rod L' is lowered in position toward the bottom of its slots v, v in the frames F, F. As shown in Fig. 8, the harnesses H and H' are in mid position, with the front lease-rod L lowered somewhat while the rear one L' is correspondingly raised; and in Fig. 9 the harnesses are shifted the entire distance, while the position of the two lease-rods is reversed from that shown in Fig. 7, the front rod L being near the lower end of its slots v, and the rear rod L' being at the top of the slots v which are represented by dash lines. In this manner the two lease-rods L, L' are caused to oscillate up and down about a central axis which is substantially coincident with the top of the fixed bar or rest T. The extent of this oscillating motion of the lease-rods is variable with the vertical adjustment of the fixed bar T and may be regulated as required to give the best results. The effect of this alternate shifting of the lease-rods is to regulate the tension of the two sets of warp-yarns w and w' whereby the upper yarns remain relatively slack during the insertion of the filling while at the same time being held under

sufficient tension to prevent them from interfering with the passage of the shuttle through the shed. This slackening of the yarns allows the filling thread to be beaten up into the fell of the cloth with the warp-yarns disposed in parallel alinement at equal intervals thereacross. In other words, it prevents the tension on the warp from drawing the alternate yarns w and w' together where they pass through the reeds in pairs and therefore eliminates the uneven spacing or pairing of the yarns which gives the reedy appearance to the finished cloth as illustrated in Fig. 2. Stated briefly, the oscillation or play of the lease-rods serves to control the tension on the warp-yarns in such manner as to permit them to lie straight under equalized distribution across the fabric, thereby improving the texture and giving a superior finish to the goods.

Fig. 6 illustrates a modification in the arrangement for supporting the lease-rods L and L', showing means for rocking the rods positively. In this embodiment of the invention the ends of the rods L and L' are rotatably mounted in opposite rocker-arms P pivoted at p on the central, fixed rod K'. A lever U is connected to one of the rocker-arms P by means of a link u and carries a stud or roll u' at its opposite end engaging a groove or track z in the heart-cam Z. The cam Z may be driven from the harness-motion cam-shaft of the loom, or through any other suitable connections, and its rotation acts to oscillate the lever U to rock the arms P to move the lease-rods L, L'. In this manner a positive motion is imparted to the lease-rods to oscillate them about the central rod or warp-rest K', the movement of the rods being synchronized with the shifting of the harnesses in the same manner as before described. It is obvious that a crank-motion might be substituted for the cam Z, or any other form of reciprocating-mechanism may be used to rock the lease-rods as best adapted for the purpose required.

As before stated, the particular object of my improvement is to provide for the uniform spacing or equal distribution of the warp-yarns in the cloth, but in addition to this feature the use of the invention makes for other advantages as now explained: In the first place, the rocking motion of the lease-rods acts to open up the warp in lease to prepare it for the weaving operation, while smoothing and straightening out the individual yarns in parallelization; it also allows for weaving under less warp tension, since the yarns are supported between the whip-roll and the harness and controlled at a point the same distance back of the harness as the fell is in front thereof; the warp being controlled relatively close to the har-

ness tends to steady the latter, especially when steel heddles are used, preventing lateral sway or distortion thereof, thus reducing warp breakage, whereby the loom production is appreciably increased; the control on the yarns further prevents arching of the warp at the center of the harness, thereby insuring a full opening of the shed clear across the loom which guards against over-shots or undershots; in addition, the relief of tension through the use of the device reduces the strain on the harness-cams and other parts of the shed-motion of the loom, allowing an increased speed of operation of the loom. As regards the product of the loom, it has been determined that cloth woven with the use of my improved attachment will measure an inch or more wider than under ordinary conditions, using the same sley, and furthermore in addition to its superior finish its strength is increased to a very considerable extent.

Various modifications might be made in the form and construction of the parts of my improved apparatus without departing from the spirit or scope of the invention; therefore, without limiting myself to the exact embodiment shown and described, what I claim is:—

- 30 1. In a warp-controlling device for looms, the combination with the weaving-mechanism thereof, of a fixed bar extending horizontally across the loom beneath the warp at the rear of the harness, two lease-rods adapted for insertion through the warp one on either side of the fixed bar, and means to guide the ends of said lease-rods to allow them to oscillate up and down as the harness is shifted to different positions, said bars arranged to move in an arcuate path about a central axis which is substantially
- 35
- 40

coincident with the top of the fixed bar so as to maintain both sets of warp-yarns constantly bearing on the bar in whatever position the harness may be shifted to.

2. In a warp-controlling device for looms, the combination with a fixed warp-rest extending across the loom beneath the warp at the rear of the harness, two lease-rods arranged parallel with the warp-rest on opposite sides thereof, means for guiding said lease-rods at their ends while allowing them to oscillate up and down in relation to the warp-rest during the shifting of the harness, and means for adjusting said warp-rest at different heights in relation to the whip-roll of the loom to adapt it to be set in such relation that the oscillation of the lease-rods during the reciprocation of the harness will cause both sets of warp-yarns to bear constantly on the top of the warp-rest in whatever position the harness may be shifted to.

3. In a warp-controlling device for looms, the combination with the loom-frame, of supporting-members vertically adjustable in position on the opposite sides of the frame, a horizontal warp-rest supported at its ends by said members, a pair of lease-rods arranged on opposite sides of the warp-rest and parallel therewith, and means on the supporting-members for guiding the lease rods at their ends to adapt them to slide up and down when oscillated by the movement of the warp-yarns under the action of the harness, said oscillating movement of the lease-rods causing both sets of warp-yarns to bear constantly on the top of the warp-rest in whatever position the harness may be shifted to.

In testimony whereof I affix my signature.

GORDON A. JOHNSTONE.
